JAMES W. BANFIELD, OF TORONTO, OHIO, ASSIGNOR TO FOLLANSBEE BROTHERS COMPANY, OF PITTSBURGH, PENNSYLVANIA, A CORPORATION OF PENNSYLVANIA

POLISHING DEVICE FOR FURNACE CONVEYERS

Application filed March 22, 1929. Serial No. 349,028.

This invention relates to polishing devices for furnace conveyers, and more particularly to furnace conveyers of the disk type.

In a continuous normalizing or annealing furnace used in the treatment of metal sheets, disks or rolls are provided within a furnace upon the peripheries of which the sheets rest and are moved through the furnace by rotation of the disks. After the conveyer has been 5 in operation for a period of time, minute projections, of more or less degree, appear on the peripheries of the disks or rolls and, unless removed, increase in size to the point where they scratch or pit the sheets or other material 10 being conveyed, thereby marring or otherwise rendering the sheets unfit for use. These conveyer disks or rolls of a continuous furnace, due to their location within the furnace, are rendered inaccessible for the purpose of 15 removing these projections from the disks except by dismantling the furnace and removing the disks and their shafts and subsequently polishing same by use of abrasive wheels or other abrasive treatment.

20 The primary object of the present invention is to provide a device of this character which enables the disks or rolls to be polished while in the furnace and, at the same time, to provide a device in which same is partly operated by the movement of the rolls themselves.

25 A further object of the invention is to provide a device of this type which is of simple and economical construction, which can be easily operated in the reverse direction, thereby imparting a reciprocatory movement to the device so as to enable same to effect easy and quick polishing of the rolls with a minimum of time and labor.

30 In describing the invention in detail, reference is herein had to the accompanying drawings, in which:—

Fig. 1 is a horizontal sectional view of the invention applied to the conveyer of a furnace or the like, the latter being shown in fragment, and—

Fig. 2 is a section on line 2—2; Fig. 1.

Referring to said drawings, the furnace is generally indicated at F and has the usual transverse shafts 1 therein upon which the

conveyer disks or rolls 2 are mounted. As shown in the drawings, the disks 2 of adjacent shafts are staggered and receive thereon polishing plate 3 which latter is preferably made of metal and has transverse elongated 55 openings 4 formed therethrough. Transverse shafts 5 are mounted in bearings 6 which latter are secured to the plate or member 3. The shafts extend over or register with the openings in the direction of the length thereof and at approximately the center of the openings. Polishing units 7 are pivoted to the shafts so as to project within the openings 4 and to freely respond to the action of gravity.

These polishing units or flappers preferably have an insert of carborundum 8, which latter rests upon the peripheries of the disks or rolls, although other abrasive material susceptible of withstanding the heat may be employed, if desired. The character of the abrasive material depends on the degree or character of the polish which is desired, and in some instances metal inserts can be employed or the units or flappers themselves may be made entirely of such metal, possessing the desired characteristics to impart the necessary polish to the disks or rolls.

By referring to Fig. 1 of the drawings, it will be noted that the polishing units or flappers are preferably made of the length to engage two of the disks, and the hinge connections of said polishing units with the shafts 5 are preferably loose, so that if adjacent disks do not occupy the same level or plane, the ends of polishing units may tilt and consequently compensate for this variance in the levels of the disks so as to thereby engage each.

In operation, rotary movement is imparted to the disks in their normal direction of rotation, as indicated by the arrow in Fig. 2. The polishing device is then inserted at the feed end of the furnace and is carried through the latter by and on the disks to the opposite end of the furnace. In order to effect reverse movement of the device, a rope, cable or other suitable retracting means 9 is secured to the plate 3 and, upon the device being carried to the outlet end of the furnace by the movement 95 100

of the disks, the cable is then pulled so as to cause reverse movement of the device to the inlet end of the furnace, whereupon the rope 9 is again released and the operation is continued until the rolls have been polished to the desired extent.

From the foregoing, it will be seen that the disks themselves are utilized to move the device in one direction of its reciprocatory movement, the reverse movement or stroke being manually or otherwise performed. Thus, the device enables the rolls to be easily and quickly polished and with a minimum of labor and effort on the part of the operator.

In addition, it will be seen that, due to the openings 4, the longitudinal side edges thereof will act to remove the projections somewhat after the manner of a scraper or cutting edge to thus increase the efficiency of the device.

What is claimed is:—

1. A polishing device for furnace disk conveyors, including a plate formed to seat on the conveyer disks and be moved thereby in one direction and having transverse openings extending therethrough, shafts extending lengthwise of the openings, means to secure the shafts to the plate, a series of polishing units freely hinged to the plate and formed to engage the upper arcs of the conveyer disks, and a cable connected to one end of the plate for moving same in a direction opposite to that in which the disks rotate.

2. A polishing device for furnace disk conveyors, including a plate formed to seat on the conveyer disks and be moved thereby in one direction and having transverse openings extending therethrough, shafts extending lengthwise of the openings, means to secure the shafts to the plate, a series of polishing units freely hinged to the plates and formed to engage the upper arcs of the conveyer disks, and means connected to the plate for moving same in a direction opposite to that in which the disks rotate.

3. A polishing device for furnace disk conveyors including a member formed to seat on the conveyer disks and be moved thereby in one direction, polishing units, means to pivotally mount the units on the member so that same freely engage the upper arcs of the disks, and means to move the member in the opposite direction.

4. A polishing device for furnace disk conveyors including a member formed to seat on the conveyer disks and be moved thereby in one direction, polishing units, means to movably mount the units on the member to cause same to engage against the upper arcs of the disks, and means for moving the member in the opposite direction.

5. A polishing device for furnace disk conveyors, including polishing means formed to seat upon the disks and to be moved thereby in one direction, and means connected to

said polishing means for moving same in the opposite direction.

In testimony whereof, I affix my signature.

JAMES W. BANFIELD.
